UNITED STATES PATENT OFFICE.

ALEXANDER L. GEITNER, OF ROCHESTER, NEW YORK.

FACING-TOOL.

1,240,701.

Specification of Letters Patent. Patented Sept. 18, 1917.

Application filed April 16, 1917. Serial No. 162,548.

To all whom it may concern:

Be it known that I, ALEXANDER L. GEITNER, a citizen of the United States, residing at Rochester, N. Y., in the county of Monroe 5 and State of New York, have invented certain new and useful Improvements in Facing-Tools, of which the following is a specification.

The object of this invention is to provide 10 a new and improved form of cutting and facing tool for facing off uneven places around a bolt opening and for counterboring such openings.

Another object of this invention is to 15 make this tool so that it can be readily adjusted and adapted to different sizes of openings.

These and other objects of this invention will be fully illustrated in the drawings de- 20 scribed in the specification and pointed out in the claims at the end thereof.

In the accompanying drawing,

Figure 1 is a front elevation of the tool.

Fig. 2 is a top plan view of the tool.

Fig. 3 is a side elevation of the tool.

Fig. 4 is a sectional view of the end of the tool, the section being taken on the line 4^x-4^x of Fig. 1.

Fig. 5 is a front elevation of a modified 30 form of the tool.

Fig. 6 is a horizontal sectional view of the tool, the section being taken on the line 6^x-6^x of Fig. 5.

In the several figures of the drawing like 35 reference numerals indicate like parts.

The tool as shown in the drawing consists of a cylindrical body 1 which is provided with a shank 2 on one side thereof. This shank is adapted to be held in any of the 40 well known types of tool holders which are used to hold the tool during its rotation in the machine while work is performed therewith.

On the other end and opposite to the shank 45 2 the cylindrical body 1 is provided with an extension 3 of reduced diameter. This extension has a reduced end 4 which is adapted to receive the bushing 5. The reduced end 4 of the extension 3 is hollow and is pro- 50 vided on the inside thereof with a female thread into which engages the clamping bolt 6. The head 7 of this bolt is adapted to clamp the bushing 5 against the shoulder 8 formed on the extension 3 by the reduced 55 end 4. The bushing 5 has a larger outside

diameter than the extension 3 and forms a shoulder 9 thereon for a purpose that will presently appear.

On the opposite sides the cylindrical body 1 has two slots 10 and 11 which are ar- 60 ranged diagonally to the shank. Tools 12 and 13 are inserted into these slots and are rigidly clamped in place therein by means of the set screws 14 and 15 respectively. These set screws are threaded into the body 65 1 opposite each of the slots 10 and 11 and at right angles thereto so that the tool can be rigidly clamped therein.

The tools are adjusted in the holder with 70 relation to each other by sliding each of the tools in their respective slots until the cutting edges thereof abut against the shoulder 9 formed by the bushing 5. In this manner the cutting edge of each of the tools is lined up with the other so that each 75 of these cutting edges is flush with the shoulder 9 formed on the extension 3. The tools are radially arranged in the cylindrical body 1 and their cutting edges are beveled off in opposite directions so that on the ro- 80 tation of the holder both of the tools will cut in the same direction.

The tool is shown with the slots in the cylindrical body forming a small angle with the axis of the shank. This is necessary 85 when the tool is used to cut steel or a similar material in which it has to perform a cutting operation rather than a scraping operation. If the tool is used to cut brass or copper the slots 10 and 11 should run parallel to the 90 axis of the shank of the tool so that the individual tools fastened therein will have no tendency to dig themselves into the comparatively soft material instead of uniformly scraping the material off at the 95 surface around the opening on which the tool operates.

As above pointed out the outer end of the tool is adapted to receive different sizes of bushings which have different outside 100 diameters which may be clamped to the extension 3 as previously described. In this manner the tool can be used for operating on different sizes of openings by simply changing the bushing at the end of the tool 105 to correspond with the size of the opening on which the tool is to operate.

It is also understood that the cutting edge of each of the tools 11 and 12 may have an outline other than the straight edge shown 110

in the drawing so as to adapt this tool to face off the material around the opening angularly or in any other form as may be desired.

5 In Figs. 5 and 6 is shown a modified form of clamping means for the tools 11 and 12. In this form the slots 10 and 11 are extended into a ring 16 which surrounds the cylindrical body 1 of the tool so that each 10 of the tools 11 and 12 is completely embraced by the slots 10 and 11. This construction permits the tools to be clamped edgewise toward the center of the cylindrical body 1 and for this purpose the said 15 screws 17 and 18 are provided which are adapted to force the tools from the periphery toward the center of the cylindrical body 1.

If desired the slots 10 and 11 may be completely formed in the body of the tool as 20 shown in Figs. 1 to 4 inclusive, in which case the dividing line between the ring 16 and the body 1 of the tool will be the dotted line 19 indicated in Fig. 6 instead of the 25 full line 20 shown in the same figure.

I claim:

1. A tool comprising a holder, a shank on one side of said holder, an extension of reduced diameter on the other side of said holder, a bushing carried on the end and overlapping said extension to form a shoulder thereon, slots in said holder, said slots being adapted to receive tools therein, means for independently adjusting said tools in each of said slots, the cutting edge of each of said tools being adapted to project out of said holder and abut against the shoulder formed by said bushing on said extension, clamping means provided on said holder to

adjustably clamp each of said tools in said holder.

2. A tool comprising a holder, a shank on one side of said holder, an extension of reduced diameter on the other side of said holder, a bushing carried on the end and 45 overlapping said extension to form a shoulder thereon, a ring surrounding said holder, slots in said holder, said slots being adapted to receive tools therein, means for independently adjusting said tools in each of 50 said slots, the cutting edge of each of said tools being adapted to abut against the shoulder formed by said bushing on said extension, clamping means on said ring to clamp said ring and said tools into said 55 holder.

3. A tool comprising a holder, a shank on one side of said holder, an extension of reduced diameter on the other side of said holder, a bushing carried on the end and 60 overlapping said extension to form a shoulder thereon, a ring surrounding said holder, slots in said ring, said slots being adapted to receive tools therein, means for independently adjusting said tools in each of 65 said slots, the cutting edge of each of said tools being adapted to abut against the shoulder formed by said bushing on said extension, clamping means on said ring to clamp said ring and said tools into said 70 holder.

In testimony whereof I affix my signature in the presence of two witnesses.

ALEXANDER L. GEITNER.
